CARBURETOR

Paul Xavier Auguste Gistuccci, Paris, and Johann Lichtenstein, Levallois-Perret, France, assignors to Societe Generale Des Carburateurs Zenith, Levallois-Perret (Seine), France, a corporation of Switzerland

Application June 24, 1936, Serial No. 87,094
In Belgium August 24, 1935

9 Claims. (Cl. 261—69)

The present invention relates to carburetors for internal combustion motors in which fuel is supplied to the fuel discharge nozzles by means of a reservoir in the wall of which is a diaphragm controlling a valve which regulates the supply of fuel to said reservoir. The reservoir is supplied with fuel under pressure and the diaphragm regulates the opening of the valve in such a manner as to maintain in the fuel reservoir a definite pressure. Such carburetors are already known particularly as shown in applicants' Belgian patents, No. 369,960 of May 1, 1930; No. 369,961 of May 1, 1930; No. 404,966 of August 30, 1934; and No. 406,646 of December 5, 1934.

According to the present invention a depression chamber is connected to the carburetor induction passage by a depression passage. This depression chamber comprises a movable partition, which may be either a diaphragm or a piston, and this movable partition is connected to the fuel reservoir diaphragm by a mechanical connection arranged in such a way that the force exerted by the depression on said movable partition and transmitted to said diaphragm through this mechanical connection tends to increase the opening of the valve. The force thus transmitted to the fuel reservoir diaphragm increases the value of the pressure maintained in the fuel reservoir by said diaphragm.

The design forming the subject matter of the present invention is for the purpose of increasing the supply pressure of the fuel discharge and consequently to increase the drop in pressure at the orifices discharging the fuel into the mixing chamber of the carburetor.

As is well known, at higher altitudes the relative depression in the induction passage decreases, so that the pressure drop at the fuel nozzle becomes too small to permit accurate metering or efficient atomization of the fuel. This is remedied in the present invention by increasing, with increasing altitude, the pressure under which the fuel is supplied to the nozzle. This is accomplished by bleeding air from atmosphere, or from the air entrance of the carburetor, into the depression chamber, and controlling, either manually or automatically, the amount of such bleeding so as to make it proportional to the barometric pressure.

Other objects and advantages of the invention will be apparent from the following description, taken in connection with the appended drawings, in which:

Figure 1 is a diagrammatic representation of a carburetor embodying the invention;

Figures 2, 3, and 4 are similar views showing modifications of the same; and

Figures 5, 6 and 7 represent the valve of Figure 4 in various positions.

The carburetor shown in Figure 1 comprises an induction passage 1 supplied with air through air intake 2 and controlled by throttle valve 3. Induction passage 1 is supplied with fuel through fuel nozzle 4 opening posterior to throttle valve 3 and controlled by a needle 5 actuated mechanically by throttle valve 3 through lever 6, link 7 and lever 8 pivoting at 9.

The fuel nozzle 4 is supplied by fuel reservoir 10 which in turn is supplied with fuel under pressure through a passage 11. The fuel reservoir 10 comprises a diaphragm 12 connected to a valve 13 regulating the supply of fuel to the reservoir.

Diaphragm 12 is also connected by a rod 14 to one of the arms 15 of lever 15, 16 pivoted at 17.

A depression chamber 20 communicates with the induction passage 1 through a passage 21 which opens therein at 22, preferably in the vicinity of fuel nozzle 4 in such manner that the depression transmitted to chamber 20 is approximately the same as that acting on fuel nozzle 4. Passage 21 is controlled by a valve 33 which may be manually actuated by means of a lever 34. A diaphragm 23 is placed in the wall of the depression chamber 20 and is connected by a rod 24 to the second arm 16 of lever 15, 16. The force exerted by the depression on diaphragm 23 is transmitted by the rod 24, lever 15, 16, and rod 14 to diaphragm 12 and to valve 13 and this force tends to open valve 13.

Diaphragms 12 and 23 separate respectively fuel reservoir 10 and depression chamber 20 from a compartment 25 which communicates with the carburetor intake 2 through a passage 26. Compartment 25 might, however, be omitted and diaphragms 12 and 23 then be exposed directly to the atmosphere.

An altitude corrector is provided in the form of a passage 26 which leads from compartment 25 to the air intake 2, and is provided with a calibrated orifice 27; also a passage 28 which leads from compartment 25 to the induction passage at 22 and is controlled by a valve 29 which is manually operated by means of an arm 30, to vary the relative effective cross-sections of passages 26 and 28 and thus control the depression transmitted to compartment 25. Chamber 20 also communicates with air intake 2 through passage 31 having a calibrated orifice 32.

The operation of the mechanism is as follows: The upper face of diaphragm 12 is subjected to

the pressure existing in compartment 25 and the lower face is subjected to the fuel pressure in reservoir 10. Diaphragm 12 is also subjected through rod 14 and lever 15, 16 to the force exerted on diaphragm 23 by the depression transmitted to the depression chamber 20.

The fuel pressure in reservoir 10 assumes a balanced value such that the difference between that pressure and the pressure, acting upon diaphragm 12, balances the force exerted by the depression acting on diaphragm 23. If the pressure in reservoir 10 falls below this balanced value, the forces applied to the upper face of diaphragm 12 become preponderant and diaphragm 12 is lowered and further opens valve 13. The fuel pressure in reservoir 10 rises again and balanced pressure is re-established. Conversely, if the pressure in reservoir 10 rises above the balanced value, diaphragm 12 will be raised and will tend to close valve 13 which will cause a decrease of pressure in reservoir 10 and bring about a balanced condition.

The pressure drop under which the fuel discharges from nozzle 4 is equal to the difference between the pressure in fuel reservoir 10 and the pressure in intake passage 1. The depression transmitted to the depression chamber 20 causes an increase of pressure in fuel reservoir 10 and consequently increases the pressure drop under which the fuel discharges from nozzle 4. For example, if diaphragms 12 and 23 have equal working surfaces and the arms of lever 15, 16 are equal, the difference between the pressure in fuel reservoir 10 and the pressure in compartment 25 should be equal to the difference between the pressures existing in compartment 25 and in the depression chamber 20, that is it should be equal to the depression which it should balance. The drop in pressure under which the fuel discharges from nozzle 4 is then equal to twice the depression, that is it is twice as great as it would be in a diaphragm type pressure regulator of the known type in which depression chamber 20 and diaphragm 23 are not present. At an altitude where the density of the air is half of the density of the air on the ground, the fuel in a carburetor of the type shown in Figure 1 discharges under a drop of pressure which is the same as in a carburetor of the usual type operating on the ground and which is not provided with the mechanism of the present invention.

In order that the pressure in fuel reservoir 10 may effectively be regulated by the mechanism constituting the present invention, it is evidently necessary that the fuel be supplied to reservoir 10 through passage 11 under a higher pressure than the regulating pressure in reservoir 10. During idling operation on the ground, the depression in the intake passage is around 500 grams per square centimeter. The regulating pressure in reservoir 10 for this value of depression is then also 500 grams per square centimeter. In order that the mechanism may effectively regulate the pressure in the fuel reservoir itself for this maximum value of depression, it will be necessary that passage 11 supply the fuel to reservoir 10 under a pressure higher than 500 grams per square centimeter.

The values in the above example have been chosen merely for simplicity of explanation; in general, the pressure in the fuel reservoir would not be increased in such proportions. Preferably the surface area of diaphragm 23 would not be decreased relative to the surface area of

diaphragm 12 in order that diaphragm 23 may have the degree of movement required for the operation of the device. Preferably diaphragm 23 should have the same working surface area as diaphragm 12, but the lever arm 16 should be 5 shorter than lever arm 15 in order to diminish the effort transmitted from diaphragm 23 to diaphragm 12. As a practical example, the lever arm 15 may be twice as long as lever arm 16. The pressure increase in the fuel reservoir will then 10 be equal to half of the depression, and the pressure drop under which the fuel discharges from nozzle 4 will thus be increased 50%, which as a rule will be sufficient to supply an accurate fuel proportion and give atomization of the same 15 at all altitudes practically attainable. For the maximum depression, which is approximately 500 grams per square centimeter, the corresponding pressure in reservoir 10 would be 250 grams per square centimeter, which will be sufficient if passage 11 supplies fuel under a pressure higher than 250 grams per square centimeter in order that the pressure regulator may function effectively under all operating conditions.

It is evident that the section of fuel discharge 25 nozzle 4 is smaller in the arrangement shown in Figure 1 than in a carburetor not comprising the mechanism of the present invention.

The depression transmitted to compartment 25 causes the diminution of regulating pressure in 30 fuel reservoir 10 and consequently decreases the discharge of fuel. This diminution becomes greater as the depression transmitted to compartment 25 increases. The operation of lever 30 thus permits the proportion of the mixture 35 delivered by the carburetor to be varied as the altitude varies. Obviously, lever 30 may be operated automatically, or instance by means of an aneroid capsule.

By regulating the depression transmitted to 40 depression chamber 20 it is possible to regulate the force transmitted to diaphragm 23 and diaphragm 12 and consequently to modify the quantity of fuel supplied by a fuel nozzle 4, that is it is possible to modify the richness of the mixture 45 supplied by the carburetor.

Lever 34 allows the modification of the section of depression passage 21 relative to the section of calibrated orifice 32 and permits consequently the modification of the depression 50 transmitted to depression chamber 20. Valve 33 may obviously be replaced by a valve located in passage 31 or else by regulating means modifying simultaneously the sections of passages 21 and 31.

When valves 29 and 33 are closed, the pressure on the two faces of diaphragm 23 is the same and the mechanism functions as if diaphragm 23 and chamber 20 were omitted. Then if membranes 12 and 23 are of equal area and lever arms 15 and 16 of equal length, as shown, valve 33 may be opened to such extent as to transmit to the depression diaphragm 20 a depression equal to 20% of the depression existing in intake passage 1 at the end 22 of depression passage 65 21, whereupon the quantity of fuel supplied by fuel nozzle 4 will be increased approximately 10% and the mixture is enriched accordingly. In order to obtain the same enrichment in a device wherein arm 15 is twice as long as arm 16, it 70 would be necessary to transmit to depression chamber 20 a depression equal to 40% of the depression existing at 22 in the intake passage 1. In an important application of the present invention a carburetor would be regulated in such 75

a manner as to supply a lean mixture for economical operation when valve 33 is closed and a rich mixture permitting the motor to develop its maximum power when valve 33 is open. A suitable calibration may be provided in valve 33 or in passage 21 in order that a full opening of valve 33 may correspond to the correct rich mixture allowing the motor to develop its full power.

In the arrangement shown in Figure 1, the enrichment obtained for a given position of valve 33 is not constant, since it depends on the depression transmitted to compartment 25, that is it depends on the position of valve 29. This shortcoming is overcome in the carburetor shown in Figure 2. In this carburetor the air conduit 31 of the carburetor shown in Figure 1 is replaced by a passage 35 connecting the depression chamber 20 to compartment 25. A calibrated orifice 36 is placed in passage 35. Preferably the section of orifice 36 should be small relative to the section of orifice 27 in order that escape of air which is taking place through orifice 36 when valve 33 is open does not modify proportionately the depression which is transmitted to compartment 35 and which is regulated by means of valve 29.

The carburetor shown in Figure 3 represents a variation of the carburetor shown in Figure 2 in which the depression transmitted to compartment 25 is regulated automatically as a function of the depression existing in the intake passage 1 as was described in applicants' Belgian Patent No. 406,646.

In Figure 3 a chamber 37 communicates freely through passage 41 with depression port 22 which opens into the induction passage 1. The pressure existing in chamber 37 is then the same as the pressure existing at 22. Depression passage 21 controlled by valve 33 opens into chamber 37 the same as passage 28 of Figures 1 and 2 which transmits the depression to compartment 25.

Valve 29 in Figure 2 which controls the section of passage 28 is replaced in Figure 3 by a profiled rod 40 controlling a calibrated orifice 39 and attached to an expansible capsule 38 located in chamber 37. Capsule 38 expands or contracts as a function of the pressure existing in induction passage 1 in such a manner that the section of the orifice passage 39 and the relation between this passage section and orifice 27 is regulated by rod 40 as a function of the pressure in induction passage 1. By suitably profiling rod 40, a full automatic carburetor is obtained both in its operation on the ground and at altitude, that is the proportion of the mixture supplied by the carburetor remains correct irrespective of throttle opening, motor speed, or altitude. Under these conditions the carburetor may be regulated (by suitably profiling needle 5) in such a manner as to supply a lean mixture for economical operation when valve 33 is closed and to supply a richer mixture for normal operation or to allow the motor to develop its full power when valve 33 is open.

According to actual experience with aviation motors a motor may be supplied with a mixture called "normal mixture" at medium openings of the throttle valve but it is necessary to supply the motor with a richer mixture at full throttle opening to permit the motor to develop its maximum power and on the other hand to avoid the burning of the exhaust valves which would take place with normal mixture. It is equally necessary to furnish a richer mixture at slight openings of the throttle in order to improve the flexi-

bility of the motor. In order to decrease the fuel consumption, it is possible to lower the mixture richness below the so-called normal mixture richness, which already is a relatively lean mixture, but this mixture cannot be used at large throttle openings without danger to the valves and it is equally preferable not to use it at slight openings of the throttle valve.

Figure 4 shows a variation of the carburetor shown in Figure 3 in which a leaning arrangement controlled by the pilot permits switching from normal mixture to lean mixture. A second arrangement controlled by the throttle valve renders the leaning arrangement inoperative at large openings of the throttle valve, that is even if the pilot leaves the leaning arrangement in the "lean" position, when the throttle valve is brought into wide open position or into the idling position this second arrangement intervenes to re-establish normal mixture. This second arrangement furthermore may enrich the mixture at wide open throttle positions and in idling positions of the throttle valve.

In the arrangement shown in Figure 4 depression passage 21 comprises a valve 42 which can be operated by the pilot by means of lever 43. The "leaned" position of the leaning arrangement corresponds to the closed position of valve 42, while the open position of this valve as shown in the drawings corresponds to the "normal" position of the leaning arrangement. Section 45 of passage 21 between the valve 42 and depression chamber 20 is provided with a calibrated orifice 44. Passage 45 communicates through passage 46 with body 47 of valve 48. Valve 48 is operated by lever 49 connected by link 50 to lever 51 fixed to the axis of throttle valve 3. The valve body 47 communicates also with chamber 37 through passage 52 and with depression chamber 20 through passage 53 which is provided with a calibrated orifice 54. Valve 48 has four parts 55, 56, 57 and 58.

In Figure 5 valve 48 is shown in a position corresponding to wide open position of throttle valve 3.

In Figure 6 it is shown in a position corresponding to an intermediate position of the throttle valve, while in Figure 7 it is shown in a position corresponding to the closed position of the throttle valve.

If both of valves 42 and 48 are closed, depression chamber 20 then communicates only with compartment 25 through orifice 36, with the result that the pressure on both sides of diaphragm 23 is the same and diaphragm 23 does not transmit any force to diaphragm 12. The mixture supplied by the carburetor under these conditions is a so-called lean mixture.

If passage 45 communicates with chamber 37, passage 53 still being shut off by valve 48, the depression chamber 20 communicates then with the intake passage 1 through calibrated orifice 44. A certain depression is then transmitted to chamber 20 and diaphragm 23. The mixture is then richer than in the preceding case and constitutes so-called normal mixture.

If both passages 45 and 53 communicate with the chamber 37, depression chamber 20 communicates with intake passage 1 through both calibrated orifices 44 and 54. The depression transmitted to the depression chamber 20 is still greater and the mixture is still richer. The mixture supplied by the carburetor under these conditions is a so-called rich mixture.

When lever 43 is placed in "normal" position, 75

valve 42 is opened and depression chamber 20 communicates with chamber 37 through passage 45 no matter what the opening of the throttle valve.

5 At medium openings of the throttle valve (Figure 6) the passage 53 is closed by valve 48 and the mixture delivered is normal.

At wide open position of the throttle valve (Figure 5) passage 53 communicates with passage 52 and chamber 37 through channels 58 and 56 of valve 48. The mixture supplied is rich.

When the throttle valve is in the vicinity of its closed position (Figure 7) passage 53 still communicates with passage 52 and chamber 37 through channels 57 and 55 of valve 48. The mixture supplied is still rich.

When lever 43 occupies the "lean" position, valve 42 is closed and the operation of the arrangement is as follows.

20 At medium openings of the throttle valve (Figure 6) the three passages 52, 46 and 53 are shut off by valve 48. As valve 42 is also closed, depression chamber 20 has no communication with the induction passage 1 and the mixture supplied is lean. At full opening of the throttle valve (Figure 5) passage 45 communicates with passage 52 and chamber 37 through passage 46 and channels 55 and 56, while passage 53 communicates with passage 52 and chamber 37 through channels 58 and 56. The mixture supplied is rich even though lever 43 is in "lean" position.

When the throttle valve is in the vicinity of its 35 closed position (Figure 7) passage 45 communicates with passage 52 and chamber 37 through passage 46 and channels 58 and 55 while passage 53 communicates with passage 52 and chamber 37 through channels 57 and 55. The 40 supplied mixture is rich even though lever 43 is in "lean" position.

It can be seen from the drawing that the different channels in valve 48 are larger than the outlets of the different passages opening into 45 valve body 41. Because of that, passages 46 and 53 begin to communicate with passage 52 when the throttle valve is not yet completely closed. A rich mixture is thereby obtained at slight openings of the throttle valve before the 50 same is completely closed, the angle of the opening below which the rich mixture is attained being governed by the size and location of these channels.

The location of the channels is such that when 55 the throttle valve is closed from wide open position (Figure 5), passage 53 is shut off immediately while passages 46 and 52 remain in communication until the throttle valve is closed to a certain angle. The calibrated orifice 54 is then 60 shut off from communication with chamber 37 while orifice 44 continues to communicate with that chamber through passages 45, 46 and 52. The mixture is then normal even though lever 43 occupies the "lean" position. The location and 65 size of the channels of valve 48 permit the determination of the opening angle above which the leaning arrangement is rendered inoperative.

It is evident that if one wishes to accomplish 70 by means of valve 48 only part of the functions which it serves in the arrangement shown in Figure 4, those valve channels or passages opening into its valve body may be omitted which correspond to the functions that it is not desired to accomplish.

75 If it is desired not to produce by means of

valve 48 an enrichment at closed or slightly opened positions of the throttle valve, channel 57 of valve 48 may be omitted. The enrichment at slight openings may then be obtained by a suitable profiling of needle 5 which regulates the fuel discharge at nozzle 4; likewise the enrichment at wide throttle openings obtained by the operation of valve 48 may be eliminated by omitting passage 53, and this enrichment can be obtained by a suitable profiling of needle 5. 10

If finally it is desired not to render inoperative the leaning arrangement at slight openings of the throttle valve, it will suffice to re-locate channel 58 of valve 48 and corresponding channel 57 in the outlet of channel 53 in the valve body 41 in such a manner that channel 58 does not register with passage 46 at slight openings of the throttle valve.

We claim:

1. In a charge forming device for an internal combustion engine, an induction passage, a throttle controlling the same, a fuel nozzle discharging in said induction passage posterior to the throttle valve, a fuel chamber connected to said nozzle and having a movable wall, a valve controlling the inflow of fuel to said chamber and connected to said movable wall, a depression chamber having a movable wall connected to the first mentioned movable wall, a depression conduit connecting the depression chamber to the induction passage posterior to the throttle, a second conduit connecting the depression chamber to the induction passage anterior to the throttle, and means operated in accordance with the throttle position for varying the cross section of one of said conduits.

2. The combination defined in claim 1, comprising in addition a compartment interposed between the fuel chamber and the depression chamber and having in common therewith the movable walls thereof, said compartment communicating with the induction passage anterior to the throttle.

3. The combination defined in claim 1, comprising in addition a compartment interposed between the fuel chamber and the depression chamber and having in common therewith the movable walls thereof, and a restricted connection between the depression chamber and the compartment.

4. In a charge forming device for an internal combustion engine, an induction passage, a throttle controlling the same, a fuel nozzle discharging in said induction passage, a fuel chamber connected to said nozzle and having a movable wall, a valve controlling the inflow of fuel to said chamber and connected to said movable wall, a depression chamber connected by a depression passage to said induction passage posterior to the throttle and having a movable wall also connected to said valve, a conduit connecting the depression chamber to the induction passage anterior to the throttle, means including said movable walls forming a chamber communicating with said conduit, and pressure responsive means for varying the relative effective cross sections of the depression passage and the conduit.

5. The invention defined in claim 4, wherein the pressure responsive means comprises a valve the operation of which is controlled as a function of the pressure obtaining in the induction passage posterior to the throttle.

6. The invention defined in claim 4, com-

- prising in addition a manually operated valve controlling the depression passage.
7. In a charge forming device for an internal combustion engine, an induction passage, a throttle controlling the same, a fuel nozzle discharging in said induction passage, a fuel chamber connected to said nozzle and having a movable wall, a valve controlling the inflow of fuel to said chamber and connected to said movable wall, a depression chamber connected by a depression passage to said induction passage posterior to the throttle and having a movable wall also connected to said valve, a conduit connecting the depression chamber to the induction passage anterior to the throttle, pressure responsive means for varying the relative effective cross sections of the depression passage and the conduit, and means actuated by throttle movements for controlling the conduit.
8. In a charge forming device for an internal combustion engine, an induction passage, a throttle controlling the same, a fuel passage discharging in said induction passage, a fuel chamber connected to said fuel passage and having a movable wall responsive to pressures in the chamber, a valve controlling the inflow of fuel to the chamber and connected to said movable wall, a depression chamber connected by a depression conduit to said induction passage and having a movable wall also connected to said

valve, a conduit connecting the depression chamber to the induction passage anterior to the throttle, means jointly responsive to throttle position and barometric pressure for varying the relative effective cross sections of said conduits, and means controlled in accordance with throttle position for varying the effective cross section of said fuel passage.

9. In a charge forming device for an internal combustion engine, an induction passage, a throttle controlling the same, a fuel nozzle discharging in said induction passage, a fuel chamber connected to said nozzle and having a movable wall responsive to pressures in the chamber, a valve controlling the inflow of fuel to the chamber and connected to said movable wall, a depression chamber connected by a depression passage to said induction passage and having a movable wall also connected to said valve, a conduit connecting the depression chamber to the induction passage anterior to the throttle, pressure responsive means for varying the relative effective cross sections of said conduits, a compartment comprising said movable walls, a calibrated orifice between said compartment and said depression chamber, and a connection between the compartment and the induction passage.

PAUL XAVIER AUGUSTE GISTUCCI.
